UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

ELECTRIC SWITCH.

Application filed July 31, 1920. Serial No. 400,397.

To all whom it may concern:

Be it known that I, HENRY T. PAISTE, a citizen of the United States, residing in Philadelphia, Pennsylvania, have invented 5 the Electric Switch of which the following is a specification.

One object of my invention is to provide an electric switch involving a novel construction and arrangement of parts, permitting the ready insertion and removal of 10 fuse plugs; the invention more especially contemplating such a disposition of the elements as will insure current being cut off from the exposed parts of the device when 15 these are accessible.

Another object of my invention is to provide a fused switch of the enclosed type, whose construction shall be such that the act of opening the switch container will necessarily 20 open the switch and at the same time cut off the fuse terminals from the live current conductors or terminals so that the fuse or fuses may be safely removed;—the arrangement of the parts being such as to insure 25 that the circuit through the switch cannot be completed until the fuses with their terminals and the conducting parts of the switch have been brought to such positions that they are no longer accessible.

I further desire to provide an electric switch which shall include a container of 30 novel form having a lid or cover made in a plurality of parts respectively carrying stationary and movable contacts so associated that opening of the container necessarily 35 opens the switch, and closing of the container renders the parts of the switch inaccessible without completing the circuit therethrough,—such completion of the circuit or closure of the switch being accomplished by an operator at any time desired 40 after the closure.

My invention is also designed to provide 45 an electric switch whose movable element automatically moves to its open position when the cover of the switch-enclosing casing is opened, and remains in said open position during and after the movement of said cover to its closed position until closed by hand.

I also desire to provide a switch of the above noted type having a novel mounting for its terminals and their associated parts whereby these are rendered readily accessi-

ble without exposing the main portions of 55 the switch.

These objects and other advantageous ends I secure as hereinafter set forth, reference being had to the accompanying drawings, 60 in which;

Figure 1, is a perspective view illustrating the enclosing casing of my switch;

Figs. 2 and 3, are longitudinal vertical sections illustrating the movable switch member in its closed and open positions 65 respectively;

Fig. 4, is a section similar to that of Fig. 2, showing the casing cover in its open position;

Fig. 5, is an inverted plan of the cover 70 and parts carried thereby;

Fig. 6, is a plan of the insulating blocks carried by the cover with certain of the parts associated therewith;

Fig. 7, is a vertical section on the line 75 7—7, Fig. 5;

Fig. 8, is a fragmentary side elevation illustrating the cover with the parts in the positions occupied when it is desired to expose the switch terminals;

Fig. 9, is a plan of the structure shown 80 in Fig. 8, and

Fig. 10, is a fragmentary perspective view illustrating a detail of the casing and cover.

In the above drawings, 1 represents a sheet metal box having a cover made in three parts, 2, 3 and 4, to which the two first are connected by a hinge 5, and the two last are likewise connected by hinges 6. Said cover 90 is downwardly flanged, and the intermediate section 3 thereof is normally immovably fixed to the body 1 by a pair of screws 7 extending through its opposite flanges into the sides of said body. The rear section 4 95 is also normally fixed to the body so as to be immovably held by a pair of pressed-out tongues 8 projecting from its rear flange through openings 9 in the back or rear side of said body. The arrangement is such, 100 however, that when the screws 7 are removed, as shown in Fig. 8, and the front section 2 of the cover raised, said cover as a whole may be moved rearwardly on the body 1 until the tongues 8 are withdrawn 105 from their holes 9, when the rear cover section 4 may be swung up. With the tongues 8 entered in their holes 9 and the screws 7

rigidly holding the section 3 to the body, the front cover section 2 is normally held in its closed position by spring tongue 10 fastened to the front of the body and projecting through a slot in said cover section,—there being a projection on said tongue extending over the top of the cover section 2 so as to hold it closed.

Mounted on the intermediate cover section 3 and projecting downwardly into the body of the casing 1, is a terminal block 11 of insulating material, rigidly held in place by screws 12 or other suitable means and extending for practically the entire width of said box. In the present instance, this block is provided with four wells or deep recesses 13 extending upwardly from its under side, and in each of these is a pair of spring clips 14. Each of these latter has a terminal 16 projecting rearwardly from the bottom of its particular recess into a chamber 15 formed in the upper face of a portion 17 of said block which projects under the third cover section 4, and with the construction shown, there are four of these terminal projections 16, each having a conductor-clamping screw 18 exposed when said cover section 4 is swung upwardly to permit of the attachment or disconnection of a conductor.

The front wall of each of the recesses 13 is formed with a narrow slot 19 lying in the plane of the space between its adjacent switch clips 14 to permit of the entrance thereto of switch blades 20 or 21, which project downwardly and rearwardly from a block 23 of insulating material fixed to the front cover section 2 by a series of screws 22, and extending like the terminal block 11, for practically the full width of the casing and cover. At the outer forward corners of this block are formed two integral downwardly projecting hollow cylindrical structures 24, in each of which is mounted a threaded shell 25 inwardly flanged at its lower end so as to electrically engage the forward end of a metal plate or bar 26 extending rearwardly to and integrally connected with one of the switch blades 20. The end or head of this plate 26 engaged by the flange of the threaded shell 25, is centrally recessed to fit over an integral projection of the block, and the shell is held against this part of the said plate by a screw 27 having a washer 28 under its head, which in turn acts on an insulating washer 29 to clamp the parts together. The end of said screw enters a plate or bar 30 set in a suitable recess in the top face of the block 23 and having electrically connected to it a pair of clips 31, to which is pivoted the switch blade 21. These two latter switch blades lie between the two blades 20, which are rigidly fixed to and necessarily move with the block 23 and main portion 2 of the

cover, although their shape is generally similar to that of said outer blades. They are, however, rigidly connected by a cross bar 32 of insulating material, which is centrally slotted for the reception of an arm or bar 33 pivoted on a spindle 34 rotatably mounted in a suitable bearing preferably provided by a plate 35 held by a screw 36 to the under side of the cover section 2.

Also pivoted to this same spindle is an operating arm or handle 37, which adjacent a projecting portion 38 of the bar or arm 33, has a pin 39 formed to enter a slot 40 in said portion so that the arm 33 and operating handle 37 have a certain limited amount of relative movement, although aside from this being operatively connected together.

A spring 41 extends between the arm or bar 33 and the downwardly projecting end of a plate 42 so that through said bar the two blades 21 are at all times urged toward a position distant from their co-operating clips 14.

By the above described arrangement of parts, it will be understood that the screws 7 normally hold the cover parts 3 and 4 rigidly to the body of the box, and if the section 2 be in its closed position, it is possible by means of the handle or operating member 37 to so swing the blades 21 on their pivots as to cause them to engage their co-operating clips 14. If the retaining catch 10 be so moved as to release the cover section 2 and the latter be swung upwardly on its hinge, it necessarily carries with it the rigidly attached block 23 and the parts carried thereby, so that the blades 20 as well as the blades 21 are withdrawn from engagement with their clips 14, so that said blades as well as all parts of the fuse receptacles comprised by the shells 25 and screws 27 are cut off from the live portions of the switch comprised by the clips 14 and the terminals 16.

As the cover section 2 with its attached parts is swung up, the spring 41 acts through the bar 33 on the blades 21, so that as soon as these clear their clips 14, they are swung on their pivots toward the insulating structures 24 in which are mounted the shells 25. It is now possible to insert fuse plugs in the receptacles, and obviously all danger of injury from accidental blowing of said fuses or unintentional contact with live parts of the switch is absolutely prevented, since as above noted, all metallic parts on the block 23 are dead and access to the parts 14 and 16 is quite an impossibility owing to the formation of the block 11.

If it now be desired to put the switch into service, the cover section 2 is swung to its closed position and the blades 20 are thereupon brought into electrical engagement with their co-operating clips 14.

Owing, however, to the continued action of the spring 41, the blades 21 remain in their extreme open positions, so that even when the cover section 2 is in its fully closed position, current cannot flow through the switch. Thereafter when desired, the handle 37 may be swung forwardly, whereupon the blades 21 are caused to engage their clips 14, and current can flow through the switch.

10 As before noted, however, the act of opening the cover section 2 not only frees the two pairs of blades 20 and 21 from their clips 14, but also permits the spring 41 to move the blades 21 relatively to the other blades 15 to their extreme open positions, from which it is necessary to move them by hand after the cover has again been closed, in order to complete the circuit through the switch.

For the purpose of connecting line conductors to the terminals 16, the screws 7 are removed, and the three connected cover sections 2, 3 and 4, with their attached parts are moved slightly to the rear for a distance sufficient to cause the tongues 8 to be moved 25 out of their holes 9, whereupon the section 4 may be swung upwardly so that access may be had to the clamping screws and terminals 16.

Obviously openings may be provided in 30 the front and rear walls of the casing body 1 or in any other suitable portions of the latter, to provide for the entrance of electrical conductors, and if it is desired, I may confine any conductors passing through or 35 into the casing to the side bottom portions thereof by a transverse retaining bar 50 as shown, so as to leave a clear space in and adjacent the central part of said casing in which the blades 21 and 20 may safely be 40 moved.

I claim:—

1. The combination of a casing having a cover including a fixed and a movable part; with an electrical switch in the casing having its fixed and movable contacts mounted respectively on the fixed and the movable parts of the cover.

2. The combination of a casing having a movable cover portion; a switch in the casing having at least two movable members on said movable cover portion and also having relatively fixed contact members; a fuse receptacle mounted on the cover portion and having one terminal connected to the movable contact member and the other terminal connected to the relatively fixed contact member; and means for moving the movable members.

3. The combination of a casing having a movable cover portion; a switch in the casing having at least two movable members mounted on said cover portion; with means for automatically moving one of said members independently of the other when said cover is opened.

4. The combination of a casing having a movable cover portion; a switch in the casing having two fixed contacts and two movable contacts, of which the latter are mounted on the cover portion and are movable independently of each other; with means tending to maintain one of said movable contacts in a position disengaged from its operating fixed contact.

5. The combination of a casing having a movable cover portion; a switch in the casing having two fixed members and two pivotally movable members, of which the latter are mounted on the cover portion; with a spring tending to pivotally move one of said movable members into and retain it in a position disengaged from its cooperating fixed member.

6. The combination of a casing having a movable cover portion; a switch in the casing having two fixed members and two pivotally movable members, of which the latter are mounted on the cover portion; a spring tending to pivotally move one of said movable members into and retain it in a position disengaged from its co-operating fixed member; and a fuse receptacle on the cover portion having its terminals respectively connected to said movable switch members.

7. The combination of a casing having a movable cover portion; a switch having at least two contacts fixedly mounted within said casing; a barrier of insulating material interposed between said fixed contacts and the opening closed by the cover; movable contacts mounted on the cover and formed to engage said fixed contacts only when the cover is closed; with means for moving the of said movable contacts at will independently of the other.

8. The combination of a casing having a movable cover portion; a switch having at least two contacts fixedly mounted within said casing; a barrier of insulating material interposed between said fixed contacts and the opening closed by the cover; movable contacts mounted on the cover and formed to engage said fixed contacts only when the cover is closed; means for moving one of said fixed contacts at will independently of the other; and means operative to automatically move said independent contact to its open position when the cover is opened.

9. The combination of a casing having a movable cover portion; a switch having at least two contacts fixedly mounted within said casing; a barrier of insulating material interposed between said fixed contacts and the opening closed by the cover; movable contacts mounted on the cover and formed to engage said fixed contacts only when the cover is closed; means for moving one of said movable contacts at will independently of the other; means operative to automatically move said independent contact to its

- open position when the cover is opened; and a fuse receptacle on the cover having its terminals respectively connected to said movable contacts.
5. 10. The combination of a casing having a cover removably connected thereto and including a normally fixed and a normally movable portion; an electrical switch in the casing having its fixed and movable contacts mounted on the fixed and movable parts of the cover respectively; and a fuse receptacle mounted on the cover in circuit with said contacts when the cover is closed.
11. The combination of a casing having a cover made in a plurality of parts; relatively fixed switch contacts mounted on one of said cover parts; terminals connected to said contacts and positioned to be exposed when a second one of said cover parts is opened; and movable switch members mounted on a third cover part in positions to be disengaged from the fixed contacts when said third part is moved to its open position.
12. The combination of a casing having a cover made in a plurality of parts; relatively fixed switch contacts mounted on one of said cover parts; terminals connected to said contacts and positioned to be exposed when a second one of said cover parts is opened; movable switch members mounted on a third cover part in positions to be disengaged from the fixed contacts when said third part is moved to its open position; with means for moving one of said movable switch contacts independently of the other.
13. The combination of a casing having a cover made in a plurality of movable parts; relatively fixed switch contacts mounted on one of said cover parts; relatively movable contacts mounted on the other cover part; and terminals also on one of said cover parts, connected to said contacts and positioned to be exposed when a second one of said cover parts is opened.
45. 14. The combination of a casing having a cover made in a plurality of parts; relatively fixed switch contacts mounted on one of said cover parts; terminals connected to said contacts and positioned to be exposed when a second one of said cover parts is opened; movable switch members mounted on a third cover part in positions to be disengaged from the fixed contacts when said third part is moved to its open position; with automatic means for moving one of said movable switch contacts to its open position when the cover is opened.
15. The combination of a casing having a cover made in a plurality of parts; hinges movably connecting said parts; two devices for respectively holding two of the cover parts immovably to the casing body; a switch having fixed contacts carried by one of said cover parts; terminals connected to said contacts and positioned to be exposed when the second of said cover parts is opened; and movable switch contacts carried by the third cover part in positions to be disengaged from the fixed contacts when said third cover part is opened.
16. The combination of a casing having a cover including a movable part; a barrier mounted on the fixed part of the cover and having a series of slots therein; a series of fixed contacts mounted behind the barrier and protected thereby when the cover is open; a series of movable contacts mounted on the movable part of the cover and positioned to extend through the slots of the barrier into engagement with the fixed contacts when the cover is closed; with means for moving certain of said movable contacts independently of the others out of engagement with the fixed contacts.
17. The combination of a casing having a cover including a movable part; a barrier mounted on the fixed part of the cover and having a series of slots therein; a series of fixed contacts mounted behind the barrier and protected thereby when the cover is open; with a series of movable contacts mounted on the movable part of the cover and positioned to extend through the slots of the barrier into engagement with the fixed contacts when the cover is closed, certain of the movable contacts being operative independently of the others.
18. The combination of a casing; a barrier therein; a series of fixed switch contacts having terminals protected by said barrier; a cover made in a plurality of sections of which one is positioned to expose said terminals when open; movable switch contacts carried by another section of the cover in position to engage said fixed contacts only when the cover is closed; with means independent of the cover for actuating said movable contacts.

HENRY T. PAISTE.
